UNITED STATES PATENT OFFICE.

MARY TURNER, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 14,895, dated March 18, 1884.

Application filed February 13, 1884. Term of patent 3½ years.

To all whom it may concern:

Be it known that I, MARY TURNER, of the city, county, and State of New York, have invented and produced a new and original Design 5 for a Pattern of a Lady's Costume, (numbered 9,093;) and I do hereby declare that the engraved prints accompanying this specification convey to any one accustomed to using paper patterns a clear understanding of how a garment made up by the pattern will appear.

The design shows a round walking-skirt and an overdress. The overdress exhibits a closely-fitted basque-body, a short left-side drapery displaying draping plaits in its front and 15 back edges, a wider right-side drapery crossing the front to the left-side drapery, deepen-

ing considerably toward its right-side edge, and exhibiting draping plaits in both side edges, a deep full back drapery displaying a gathering at the top, single draping plaits in 20 its front edges, and loopings at the center, coat-sleeves and a standing collar being added.

What I claim as my invention, and desire to secure by Letters Patent, is—

The design for a lady's costume, as shown 25 in the engraved prints accompanying this specification.

MARY TURNER.
